UNITED STATES PATENT OFFICE.

ERNEST H. HORN, OF WATERBURY, CONNECTICUT, ASSIGNOR TO WATERBURY CLOCK CO., OF WATERBURY, CONNECTICUT, A CORPORATION.

GEARING UNIT FOR TIME-TRAIN.

1,271,318.

Specification of Letters Patent.

Patented July 2, 1918.

Application filed December 3, 1917. Serial No. 205,142.

To all whom it may concern:

Be it known that I, ERNEST H. HORN, a citizen of the United States, residing at Waterbury, in the county of New Haven and 5 State of Connecticut, have invented a new and useful Improvement in Gearing Units for Time-Trains; and I do hereby declare the following, when taken in connection with the accompanying drawings and the characters of reference marked thereon, to be a 10 full, clear, and exact description of the same, and which said drawings constitute part of this application, and represent, in—

Figure 1 a view in elevation of a time-train gearing unit constructed in accordance with my invention.

Fig. 2 a view thereof on the line 2—2 of Fig. 1.

Fig. 3 a sectional view of a modified form 20 thereof.

Fig. 4 a sectional view of another modified form thereof.

My invention relates to an improved gearing unit for time-trains, the object being to 25 reduce the expense of producing such parts.

With these ends in view, my invention consists in a time-train gearing unit having certain details of construction as will be hereinafter described and pointed out in the 30 claims.

In carrying out my invention, as shown in Figs. 1 and 2, the gear wheel 3 is formed with a central opening 4 adapting it to be frictionally driven directly upon the pinion 35 staff 5 so as to abut against the adjacent end of a cut pinion 6, so called because its leaves are produced by cutting an integral enlargement of the staff which as shown is formed at its ends with integral trunnions 40 7 and 8. The said wheel is held against the said end of the pinion 6 by means of a special clamping-collet 9 also frictionally driven upon the staff 5 and bearing upon the adjacent face of the wheel which is thus 45 frictionally clamped between the said collet and pinion in addition to being driven upon the staff 5, whereby it is firmly held in place.

In the construction shown by Fig. 3, the gear wheel 3 is frictionally driven upon the 50 staff 10 against the adjacent face of the thick collet 11 of an ordinary lantern pinion also comprising pins 12, a thin collet 13, and a washer 14, which latter holds the pins against endwise displacement. The wheel 55 3 is held against the collet 11 by means of a

special clamping-collet 15 frictionally driven upon the staff 10.

In the construction shown by Fig. 4 of the drawings, the gear wheel 3 is frictionally driven upon the staff 16 and clamped between two special clamping-collets 17 and 18 also driven friction-tight upon the staff which in this case is furnished with a lantern pinion 19 corresponding to the lantern pinion of Fig. 3 but separated from the 65 gear wheel 3.

It will be observed that in each of the three methods shown and described of mounting the gear-wheel, the same is mainly held against rotation by surface friction 70 upon its opposite faces. On account of the thinness of the stock in these wheels, the amount of friction produced by the engagement of the metal of the wheel, with the staff itself, is small. My improved construction 75 provides a cheap and effective substitute for the common way of mounting the gear-wheels of the gearing units of the trains of clocks and watches, the common way being to provide the wheel with a relatively 80 large, concentric hole adapting it to fit over a shoulder formed upon the adjacent end of the pinion and upset or staked to hold the wheel in place after the wheel has been mounted upon it.

I claim:—

1. As a new article of manufacture, a gearing unit for time-trains, the said unit consisting of a staff mounting a pinion, a wheel frictionally driven upon the staff, and a 90 clamping-collet driven upon the staff in position to have surface engagement with one face of the wheel which it clamps against another point of surface-engagement, whereby the wheel is held against rotation upon 95 the staff by friction upon its opposite faces produced by the driving of the collet which effects, rather than the pinion, the final clamping of the gearing-unit structure.

2. In a gearing unit for time-trains, the 100 combination with a staff mounting a pinion, of a wheel driven directly upon the said staff against the adjacent end of the said pinion, and a special clamping-collet driven upon the staff against the opposite surface 105 of the wheel which is thus frictionally pinched between the pinion and the collet by the driving of the latter which effects, rather than the pinion, the final clamping of the gearing-unit structure.

3. In a gearing unit for time-trains, the combination with a staff having an integral or cut-pinion, of a wheel frictionally driven upon the staff so as to impinge upon one end 5 of the said pinion, and a special clamping-collet frictionally driven upon the staff for pinching the wheel between it and one end of the said cut-pinion, whereby the wheel is held against rotation with respect to the staff 10 by friction upon its opposite faces produced

by the driving of the collet which effects, rather than the pinion, the final clamping of the gearing-unit structure.

In testimony whereof, I have signed this specification in the presence of two subscribers. 15

ERNEST H. HORN.
